UNITED STATES PATENT OFFICE.

EDGAR M. LONG, OF OAK CITY, NORTH CAROLINA.

ROTARY ENGINE.

1,217,789.

Specification of Letters Patent. Patented Feb. 27, 1917.

Application filed January 14, 1916. Serial No. 72,064.

To all whom it may concern:

Be it known that I, EDGAR M. LONG, a citizen of the United States, and a resident of Oak City, in the county of Martin and State of North Carolina, have invented a new and Improved Rotary Engine, of which the following is a full, clear, and exact description.

My invention relates to rotary engines of the internal-combustion type. An object of the invention is to provide an efficient, comparatively non-gyroscopic engine. Another object of the invention is to provide a rotary engine of the internal-combustion type in which the successive explosions are so frequent that the resulting combustion of the fuel may be said to be continuous. A further object of the invention is to provide a rotary engine of the type specified in which the direct impact of the explosion, as well as the expansion potential of the igniting gas, is utilized.

With the above and other objects in view, the nature of which will more fully appear as the description proceeds, the invention consists in the novel construction, combination and arrangement of parts as herein fully described, illustrated and claimed. In the accompanying drawings, forming part of the application, similar characters of reference indicate corresponding parts in all the views.

Figure 1 is a section of my engine, certain parts being broken away to show the details of construction;

Fig. 2 is a vertical section on line 2 2, Fig. 1;

Fig. 3 is a similar section on line 3 3, Fig. 1;

Fig. 4 is a longitudinal section through the rotor of the engine;

Fig. 5 is a cross section through the shaft and controlling bearing therefor on line 5 5, Fig. 1;

Fig. 6 is a cross section through the rotor at the ball race; and

Fig. 7 is a diagram of the reactions taking place in the engine.

Referring to the drawings, 10 is a stator which has tubular extensions 11 directed radially from the periphery and disposed sym-

metrically at intervals of 90°. The tubular extensions 11 are flanged to receive compressors 12. The piston rod 13 of each compressor extends into the corresponding tubular extension 11. Each rod 13 is provided with a crosshead 14 forming the abutment within the stator which is guided in the corresponding tubular extension 11. Each crosshead has a roller 15 in contact with the periphery of a floating piston 16 mounted to roll in the stator 10.

A packing gland 17 maintains packing 18 on the periphery of the roller 15 and whereby the rollers are maintained firmly on the periphery of the piston 16. Bearing blocks 19 engaging the trunnions of the rollers are adjustable within the crossheads through the medium of locking screws 20, whereby braking action by the packing on the rollers is prevented.

The piston 16 has a central cone-shaped opening 21. Fitting snugly into said opening is a cone-shaped rotor 22 provided with cylindrical extensions 23 at each end of the conical portion thereof, all included within the stator. The end surfaces of the piston 16 are dished, whereby its thickness at the opening is less than at the periphery. The cylindrical portions 23 of the rotor are threaded to receive ball or roller races 24 cooperating with similar races 25 provided in the piston, balls 26 being provided between the races 24 and 25. By means of the threaded ball races 24 a tight fit is maintained between the piston and the rotor. A series of keyways 27 are formed on the ball race 24 and the portions 23 of the rotor (best shown in Fig. 6), so that for a slight degree of relative displacement between the race and the rotor there is always a pair of keyways which will fall in register and thus permit the keying of the races to the rotor.

Shafts 28 are extended from each end of the rotor eccentric therewith and preferably forming an integral part of the rotor. An eccentric bearing sleeve 29 is provided on each shaft 28. A similar sleeve 30 receives a corresponding eccentric sleeve 29, the eccentricities of the co-operating sleeves being oppositely directed. The sleeve 30 is provided with a ball or roller race 31 at the inner end

- of the sleeve. Coöperating with each race 31 is a similar race 32 adjustably mounted in the stator in a way similar to what has been described with reference to the race 24.
- 5 Each race 32 is provided with a coöperating packing gland 33 also mounted in the stator and forming an additional bearing for the outer eccentric sleeve 30 at each face of the stator.
- 10 The outer sleeve 30 extends beyond the inner sleeve 29 and the shafts 28. One of said sleeves bears in a stationary hollow casing 34, said sleeve has openings 35 on the periphery thereof within the casing, and the 15 casing has an exhaust pipe 36. The shaft 28 on this side of the engine is hollow to establish communication between the casing 34 and the exhaust cavity 37 within the rotor 22. The exhaust cavity 37 is in communication with an exhaust port 38 formed on the periphery of the rotor in a plane central with passages 39 formed in the central plane of the piston and extending from the inner to the outer periphery thereof. The width 25 of said passages 39 at the rotor is equal to the width of the exhaust port 38 and also to the charge-delivering port 40 provided on the periphery of the rotor at a suitable interval from the exhaust port.
- 30 The port 40 is in communication through a suitable passage in the rotor with a charge chamber 41 provided within the rotor. A valve 42 is provided within the passage for establishing or cutting off communication 35 between the chamber and the port 40. This valve is operable by a cam rod 43 extending from the exhaust cavity 37 through the hollow shaft 28 and out of the stationary, hollow casing 34 where means 44 are provided 40 for manipulating the rod 43 and whereby the valve 42 is maintained at its seat against the pressure of the charge. In this position of the valve the engine is inoperative.
- 45 The passages 39 in the piston decrease in depth as they approach the outer periphery of the piston, but their width increases in proportion, so that at the periphery said passages 39 extend substantially through the entire width of the piston. The axes of said 50 passages 39 are markedly oblique to the radius of the piston, in consequence of which the reactions on the two apparently unequal sides of the passage are equal, as will appear later.
- 55 The rotor 22 has on the periphery thereof a firing notch 45 adapted to register with the passages 39 and is suitably spaced from the charge delivering port 40. The notches in communication with the passage joining 60 the charge delivering port with the charge chamber through the medium of a check valve 46, checking the flow from the firing notch to the passage. A wire 47 is provided within the notch 45 which is rendered incan-

descent when starting the engine through the medium of a source of electricity 47, one pole of which is grounded. The other pole of the source is connected to the rod 43 which is insulated from the engine parts by insulator bearings 49. The wire 47 is also connected to the rod, an insulation 48 being provided for the wire in the rotor (see Fig. 3). A switch is provided in the circuit to close the current through the wire 47 when starting the engine. After the engine is started, the combustion of the fuel maintains the wire incandescent. To prevent short-circuiting, the valve 42 is provided with an insulated tip at the point of engagement with the rod 43.

80 Channels 50 establish communication between the charge chamber and the periphery of the rotor. These channels 50 form apertures on the rotor on both sides of the piston. A check valve 51 is provided between the chamber and the channels to check the flow from the chamber to the channels. The sides of the stator are in communication through conduits 52 with the outlet ends of the compressors 12. These conduits enter the stator 10 within the area always covered by the face margin of the floating piston 16. A circumferential groove 53 is provided in each face margin to receive a packing ring 54, which prevents the charge forced into the end chambers from leaking out. It will be noted that the projecting portion of the packing ring is enlarged and forms an angle with the face of the piston so that the pressure tends to move the packing ring out of the groove into engagement with the segmental plates 55 provided on the end walls of the stator to form grooves or ways for the crossheads therein.

85 The charge delivered by the compressors 12 to the end chambers will be conveyed by the passages 50 to the charge chamber 41 from which it is conducted to the charge-delivering port 40. The passage 39 in register with said port will receive the charge 90 of fuel, which charge is ready to be ignited. It will be noted from Fig. 3 that the relation of the piston, stator and rotor is such that the register between the port 40 and a 95 passage 39 takes place when the piston at the registering passage is contacting with the surface of the stator. The charge delivered to the passage 39 by the port 40 will ignite 100 when said port, during the displacement of the rotor and piston comes into communication with the firing notch 45. The explosion resulting from the established communication passes out largely through the adjacent passage 39 immediately behind, but also to a 105 certain extent through the one that furnishes the charge. The escape of the explosion through the adjacent passage 39 is due to the close proximity of said passages at the 110

105

110

115

120

125

inner periphery of the rotor, as can be seen, whereat the passages are separated by an edge 57. In consequence, the successive explosions are within very short intervals and the resulting combustion within the engine 5 may be said to be continuous.

The gases exploded within the passage 39, due to the established communication with the firing notch 45 will meet practically 10 solid resistance, due to the fact that the peripheral opening of the passage is almost completely covered by the periphery of the stator. The gases escaping through the adjacent following passages 39 enter the expansion space 58, or the chamber of varying 15 capacity. This space or chamber is full of burnt gas under the high pressure created by the preceding explosions and is substantially incompressible. Meeting this 20 yielding resistance the newly ignited gas expands, causing the rotation of the rotor and the piston therewith. The products of combustion will exhaust from the chamber as its capacity decreases from maximum to 25 minimum through the passages 39, which will then register with the exhaust port 38.

The side A—B of a passage 39 has a greater extent of surface than the side C—D, but A—B is at a correspondingly 30 greater angle to the radius of the piston, which is the radius of the circle of travel when the piston rotates upon the rotor. Since the forces exerted respectively upon the sides A—B and C—D are to each other 35 as the side elevations of these sides, these forces may be represented by lines *a* and *c*, equal in length to A—B and C—D respectively (see Fig. 7), meeting A—B and C—D at right angles at their middle points 40 *b* and *d*. The components of the force *a* and of the force *c* may be obtained by drawing the radius of the piston through the points *d* and *b* respectively. By erecting perpendiculars to the radii of the points *b* 45 and *d* the perpendiculars will be tangent to the piston's circle of travel. By completing the parallelogram for the forces *a* and *b* it will be noted that the components *F* *F* are equal and act in opposite directions, neutralizing each other; consequently 50 the forces of explosion within the passage 39 give rise to no tendency of independent rotation of the piston upon the rotor. The components *e* *g* and *h* *i* act substantially 55 in the radius of the piston; and their combined effect tends to separate the piston from the rotor by a force equal to *e*—*g* minus *h*—*i*. This tendency lessens the strain on the roller bearings of the piston 60 by counteracting, in a measure, the force of pressure applied to the periphery of the piston from the expansion space.

If desired the inner periphery of the stator 10 may be indented and a correspond-

ing indented surface formed on the piston 65 to mesh with the indented periphery of the stator. This will offer a sinuous joint between the contacting surfaces of the stator and piston and prevents slipping between the piston and stator. 70

The portions of the crossheads 14 passing beyond the margin of the piston are connected by links 59 at each face of the piston to a ring 60 which encompasses a portion 23 of the rotor. The ring has arcuate slots 75 61 at intervals of 90° engaged by the links. This connection of the crossheads and the ring causes the inward displacement of the compressor piston when the rotary piston 16 displaces outwardly the opposite compressor piston. The throttling of the engine is in the usual way, by providing automatic or manually operable means in the intake conduit 62.

The interengaging, eccentric sleeves 29 85 and 30 each have diametrically opposite, spiral slots 63 extending substantially half way around the sleeve. The slots on the inner sleeve are directed oppositely to the slots on the outer sleeve, each slot having 90 a pitch of 45°. A diametrical slot 64 is provided in the shafts 28 of substantially the same length as the slot 63, and the length of each slot 64 is that of the projection of the spiral slot 63 on to a plane. A ring 65 is mounted on to the outer eccentric sleeves to be adjustable through the length of the slot. The ring carries a pin or pins 66 projecting through all the slots of the coöperating sleeves and shafts 28. Consequently when the ring 65 is adjusted 100 on the outer sleeve the two eccentric sleeves are rotated in opposite directions upon the corresponding shaft portion through equal angles. Since the outer sleeves bear in the stator, this adjustment permits the adjustment of the rotor within the stator. To prevent an accidental displacement of the rings 65 on the corresponding sleeves, locking members 67 are threaded on the sleeves 30 to each side of the ring. The locking members, when secured against the ring, are united by a cap or union 68 in threaded engagement with the periphery of a locking member. 110

The outer eccentric sleeve 30 coöperating with the solid shaft portion 28 extends beyond said shaft portion to receive means for transmitting power, for the pin 66 which engages the slots 63 and 64 will transmit the rotary movement from said shaft portion to said sleeves, and, consequently, to the means for transmitting power from said sleeve 30. To prevent axial displacement of the shafts 120 and the inner eccentric sleeves 29, abutting members 69 are provided within the outer eccentric sleeves 30.

Under normal conditions, in starting the

engine there is always a compressed charge in the charge chamber 41; and when the rod 43 is moved in the direction of the arrow shown in Fig. 4, the valve 42 is free to be unseated by the pressure of the charge, and so is the valve 46, consequently the charge is free to enter the passage 39 which is in alignment not only with the port 40 but with one which is in alignment or in communication 10 with the firing notch 45. By closing the switch, the wire 47 is rendered incandescent, igniting the fuel mixture in the passage that is in register with the firing notch 45 and thus starting the engine.

15 While I have described the principle of operation, together with the engine which I now consider to be the best embodiment thereof, I desire to have it understood that the engine shown is merely illustrative and 20 that such changes may be made as are within the scope of the appended claims.

I claim:

1. In a rotary engine, a stator, a piston therein mounted to roll on the periphery of 25 the stator, means forming chambers of variable capacities between said piston and stator, a rotor within the piston, said piston having passages establishing communication between the rotor and said chambers, means 30 for supplying a compressed fuel charge to said passages of the piston, and means for igniting the fuel charge in said passages when said passages establish communication 35 between a chamber at minimum capacity and said rotor.

2. In a rotary engine, a stator, a piston therein mounted to roll on the periphery of the stator, means forming chambers of variable capacities between the piston and 40 stator, a rotor within the piston, said piston having passages establishing communication between the chambers and the rotor, means for supplying the rotor with a compressed fuel mixture, said rotor having means for 45 delivering the compressed fuel charge to the passages about to establish communication between the chamber at minimum capacity and the rotor, and means for igniting the charge in said passages.

50 3. In a rotary engine, a stator, a piston therein mounted to roll on the periphery of the stator, sliding abutments in said stator engaging the piston whereby chambers of variable capacities are formed between said 55 stator and piston, a rotor within the piston, said piston having passages establishing communication between the rotor and the chambers, means for supplying the rotor with a compressed fuel mixture, said rotor having means for delivering the fuel mixture to the passages about to establish communication between the rotor and the chambers at minimum capacity, means for igniting 60 the charge in the passage, said rotor hav-

ing means for exhausting the gases of combustion from the chambers as they change from maximum to their minimum capacity.

4. In a rotary engine, a stator, a piston therein mounted to roll on the periphery of the stator, sliding abutments in the stator engaging the piston and forming chambers of variable capacities between said piston and stator, a rotor within the piston, said piston having passages establishing communication between the chambers and the rotor, compressors operable by the abutments for supplying a fuel mixture to the passages at substantially the minimum capacity of a chamber, means for igniting the mixture in the passage, and means for exhausting the products of combustion from the chambers as their capacities decrease.

5. In a rotary engine, a stator having at the periphery thereof symmetrically disposed, radial, tubular extensions, a rotor therein eccentric to the axis of the stator, a piston free to turn on the rotor and mounted to roll on the periphery of the stator, abutments in said tubular extensions of the stator engaging the piston and whereby chambers of varying capacities are formed in the stator, a compressor for each tubular extension in engagement with the corresponding abutment, means for supplying a fuel mixture to said compressors, said compressors adapted to deliver the compressed fuel mixture to said rotor, said piston having passages establishing communication between the rotor and the chambers, said rotor having means for delivering the compressed fuel mixture to the passages about to establish communication between the rotor and a chamber at minimum capacity, means for igniting the compressed fuel charge after it has been delivered to the passages, said rotor having means for exhausting the products of combustion from the passages establishing communication between the rotor and a chamber decreasing in capacity.

6. In a rotary engine, a stator, a piston therein mounted to roll on the periphery of the stator, means forming chambers of variable capacities between said piston and stator at the periphery, and chambers of fixed capacities at the ends, a rotor within the piston having passages establishing communication between the periphery of the rotor and the end chambers, means for supplying a compressed fuel mixture to said end chambers, said piston having passages establishing communication between the periphery of the rotor and the peripheral chambers whereby the compressed mixture from the end chambers is fed to said peripheral chambers, and means for igniting the compressed fuel mixture as it passes through the passages to said peripheral chambers, said rotor having means for exhausting the products of com-

bustion from the peripheral chambers into the atmosphere.

7. In a rotary engine, a stator, a piston therein mounted to roll on the periphery of the stator, means forming chambers of varying capacities between the piston and stator, a rotor within the piston having a charge-receiving chamber, means for supplying the chamber with a compressed fuel mixture, said rotor having a port at the periphery thereof in communication with the charge-receiving chamber, a check valve preventing the back flow from the port to said chamber, means for operating the valve whereby the flow from the chamber to the port may be prevented, said piston having passages establishing communication between the periphery of the rotor and the chambers of varying capacities, through said passages the compressed fuel mixture being delivered by said port to the chambers at their minimum capacities, means for igniting the compressed fuel mixture in the passages after it has been delivered by the charge delivering port.
- 25 8. In a rotary engine, a stator, a rolling piston therein, including means forming chambers of variable capacities between the piston and stator, a hollow rotor within the piston, said rotor having a charge delivering port at the periphery thereof in communication with the hollow, said piston having passages establishing communication between the periphery of the rotor and the chambers, a valve adapted to check the flow from the charge delivering port to the hollow of the rotor, means for supplying the hollow of the rotor with a compressed fuel mixture, ignition means carried in a recess provided on the periphery of said rotor, and a check valve establishing communication between the charge delivering port and the recess for the ignition.

9. In a rotary engine, a stator, a rotor eccentric to the axis of the stator, shafts extending from the rotor through the stator, an eccentric sleeve on each shaft, an eccentric sleeve bearing in each end of the stator and receiving the first-mentioned eccentric sleeve, the eccentricity of said sleeves being directed oppositely, means for rotating said eccentric sleeves on the shafts through equal angles whereby the axis of eccentricity of the rotor may be adjusted within the stator, and means for locking the sleeve to the shafts in the adjusted position.

10. In a rotary engine, a stator, a rolling annular piston therein including means forming chambers of variable capacities between said piston and stator, the inner periphery of said piston being beveled, a rotor having a beveled portion engaging said inner periphery of the piston, and adjustable bearings on said rotor for maintaining a tight fit between the piston and the rotor, said piston

having passages extending from the inner to the outer periphery thereof for bringing the beveled portion of said rotor in communication with said chambers.

11. In a rotary engine, a stator, a rolling piston therein including means forming chambers of variable capacities between the periphery of the piston and stator, said piston having concave end surfaces whereby a chamber of constant capacity is formed at the ends of the stator, means for supplying a compressed-fuel mixture to said end chambers, and a packing ring on each end surface of the piston at the margin thereof, said packing ring having an annular portion disposed at an acute angle to the end surface of the piston whereby said packing ring is maintained against the end surface of the stator by the pressure of the fuel mixture in the end chambers.

12. In a rotary engine, a stator, a rotor eccentric to the axis of the stator, a piston bearing on the rotor and adapted to roll on the periphery of the stator, abutments in the stator engaging the periphery of the piston to form chambers of varying capacities at the periphery of the stator, rings about said rotor within the stator and links connecting the rings to the abutments.

13. In a rotary engine a stator, a rolling piston, sliding abutments in the stator engaging the periphery of the piston and forming chambers of varying capacities at the periphery of said piston and stator, a rotor in the piston adapted to communicate with said chambers through said piston, said piston having concave ends forming chambers of fixed capacities at the ends of said stator, compressors operable by said abutments for supplying fuel mixture to said end chambers, a ring in each of said end chambers about the rotor, links connecting the abutments to said rings, said rotor having means for conveying the mixture from the end chambers through the piston to the chambers of varying capacities, and means for igniting the mixture.

14. In a rotary engine, a stator, a rotor eccentric to the axis of the stator, a piston bearing on the rotor and adapted to roll on the periphery of the stator, abutments in the stator, a roller carried by the abutment for engaging the periphery of the piston to form chambers of varying capacities at the periphery of the stator, packing means in the abutment for the roller, and means for adjusting the roller to and from the periphery of the piston.

15. In a rotary engine, a stator, a rolling piston therein, sliding abutments in the stator, a roller associated with each abutment for engaging the periphery of the piston, packing means for the rollers in the abutments, and adjustable means for main-

taining the roller in engagement with the periphery of the piston.

16. In a rotary engine, a stator, a rolling piston therein, sliding abutments in the 5 stator, a roller in each abutment mounted to slide therein in the radial direction of the stator, means resisting the sliding movement of the roller in the abutment, and a packing gland in each abutment for maintaining 10 packing at the periphery of the roller.

17. In a rotary engine, a stator, a rotor eccentric to the axis of the stator, an annular piston bearing on the rotor and adapted to roll on the periphery of the stator, abutments 15 in the stator engaging the periphery of the piston and forming chambers of varying capacities through the periphery of the stator, said piston having passages extending between the inner and the outer periphery and disposed obliquely to the radial direction of the piston and whereby communication is established between the periphery of the rotor and said chambers, means 20 for supplying an explosive mixture to said passages, means for igniting said explosive mixture in said passages, and means for exhausting the products of combustion from 25 said passages.

18. In a rotary engine, a stator, a rotor eccentric to the axis of the stator, a piston bearing on the rotor and adapted to roll on the periphery of the stator, abutments in the 30 stator engaging the periphery of the piston and forming chambers of varying capacities 35 at the periphery of the stator, said piston having passages extending from the inner to the outer periphery, said passages being oblique to the radial direction of the piston, one side of each passage being substantially 40 tangent to the periphery of the rotor, said rotor having means for coöperating with the passages whereby communication is established by said passages between the rotor and the chambers, means for supplying the 45 rotor with an explosive fuel mixture, means for igniting the fuel mixture in said passages, said rotor having means for exhausting the products of combustion from said 50 passages through said rotor, the relation between the sides of a passage in the piston being such that the components in the passage in the direction of rotation during the explosion is balanced.

19. In a rotary engine, a stator, a rotor eccentric to the axis of the stator, an annular 55 piston bearing on the rotor and adapted to roll on the periphery of the stator, abutments in the stator engaging the periphery of the piston and forming chambers of 60 varying capacities at the periphery of the stator, said piston having passages establishing communication between the rotor and the chambers, means for supplying an explosive mixture to said passages, and

means for igniting the explosive mixture in 65 said passages, said passages being so formed that the components of the explosion on the sides thereof are balanced in the direction of rotation of the piston.

20. In a rotary engine, a stator, a rotor 70 eccentric to the axis of the stator, a piston free to turn on the rotor and mounted to roll on the periphery of the stator, sliding abutments in the stator engaging the periphery 75 of the piston, said piston having charge-receiving passages, compressors operable by the abutments for supplying an explosive mixture to the passages, and means for igniting the mixture in the passages, said rotor having means offering a reaction to the explosion of the charge in the passages and whereby the same is caused to rotate.

21. In a rotary engine, a stator, a rotor eccentric to the axis of the stator, a piston bearing on the rotor and adapted to roll on 80 the periphery of the stator, abutments in the stator engaging the periphery of the piston whereby chambers of varying capacities are formed in the stator by said piston and abutments, said piston having passages 85 establishing communication between the rotor and the said chambers, compressors operable by the displacement of the abutments for supplying fuel mixture to said 90 passages, and means for igniting the mixture in the passages, said rotor having means offering a reaction to the mixture ignited 95 within the passages.

22. In a rotary engine, a stator, a rotor eccentric to the axis of the stator, a piston bearing on the rotor and mounted to roll on the periphery of the stator during the revolution of the rotor, sliding abutments in the 100 stator engaging the periphery of the piston and whereby the space between the stator and piston is divided into chambers of varying capacities, said piston having passages establishing communication between said 105 chambers and the periphery of the rotor, compressors operable by the movement of the abutments for supplying explosive mixture to the rotor, said rotor having means for distributing the compressed mixture to the passages of the piston, and igniting 110 means carried by the rotor for exploding the mixture in the passages, said rotor at the igniting means having means for presenting a reaction to the ignited charge, substantially as and for the purpose set forth.

23. In a rotary engine, a stator, a piston 115 mounted to roll on the periphery of the stator, means forming a chamber of variable capacities intermediate said piston and stator, and a rotor in the piston adapted to communicate with said chambers through said piston, the rotary movement of the 120 rotor causing the piston to roll on the periphery of the stator.

24. In a rotary engine, a stator, a piston
therein mounted to roll on the periphery of
the stator, means forming chambers of
variable capacities intermediate said piston
and stator, said piston and stator forming
chambers of constant capacity at the ends,
means for supplying a compressed fuel mix-
ture to the end chambers, a rotor within the
piston eccentric to the axis of the stator, said
10 piston having passages establishing commu-
nication between the chambers of variable
capacities and the periphery of the rotor,
and said rotor having means for establish-
ing communication between its periphery
and the chambers of constant capacity. 15

In testimony whereof I have signed my
name to this specification in the presence of
two subscribing witnesses.
